MANUFACTURE OF TUBULAR INSULATORS FOR ELECTRIC CONDUCTORS

Paul Francois Vergés, Neuilly-sur-Seine, France, assignor
to Societe Anonyme de Telecommunications, Paris,
France

Application February 16, 1953, Serial No. 337,105

Claims priority, application France February 19, 1952

6 Claims. (Cl. 18—13)

This invention is for improvements in or relating to 15 the manufacture of tubular insulators for electric conductors.

Insulation means are already known, in which an insulating tube is disposed about an electric conductor and is simultaneously constricted at intervals in such manner as to grip the said conductor and to form an insulation having air spaces by which the dielectric properties are improved.

The conductor thus insulated may be employed as the central conductor of a coaxial pair for telecommunications. It may also be employed for the production of symmetrical pairs or quads for aerial feeders or it may be employed in any other electrical circuit.

It is also known that the constricted parts have the object of maintaining the conductor in the centre of the tubular insulator and may form grooves which secure the conductor in position and also provide a fluid-tight partitioning which is capable of preventing accidental circulation of water within the said tubular insulator.

The known devices for producing such insulators consist of fixed or movable jaws disposed at intervals and produce constrictions when closed. However, they do not give perfect results and also are capable of treating only such materials as paper or unvulcanised rubber, that is, materials having a certain rigidity, whereas if a method of this nature is applied to very plastic materials leaving an extrusion machine, for example polyethylene plastics, the intermediate tubular portions between the constricted parts yield and become flattened and deformed, and the result obtained is very bad. The apparatus according to the present invention overcomes these serious disadvantages.

According to the present invention there is provided an apparatus for the continuous shaping of an extruded insulating plastic tube for an electric conductor, which is formed around the said conductor during the hardening of the extruded material, wherein there are employed a plurality of endless belts of rubber or plastic material having moulded bosses thereon and further provided with gear teeth for maintaining the said bosses in a suitable position in relation to one another and for driving the said belts by a sprocket wheel mechanism the said conductor being fed with a continuous movement between the said belts and at a linear speed equal to that of the said belts, while a gas pressure is maintained within the said tube in order to ensure the application of its outer surface against the said bosses, the said belts forming, in those of their parts which are in contact with one another, a continuous mold surrounding the said tube.

If polyethylene or any other thermoplastic product is employed, the operation is effected with a cooling action, and if vulcanisable material, such as rubber or thermosetting material is employed, the said operation is effected in an enclosed space which is heated throughout the period necessary for the conversion of the soft material into hardened product.

The present invention will be more particularly de-

2

scribed with reference to the accompanying drawings in which:

Figure 1 illustrates the general known form of a conductor provided with a tubular insulation of the type obtained by means of the apparatus according to the present invention,

Figures 2 and 3 illustrate the apparatus for the manufacture of insulation in accordance with the present invention,

Figures 4 and 5 illustrate details of the construction of the apparatus as illustrated in Figure 2, and

Figures 6, 7, 8 and 9 illustrate by way of example new forms of tubular insulation which can be obtained by means of the apparatus as illustrated in Figures 2 and 3.

Referring to the drawings and in particular to the apparatus illustrated in Figure 2, the dies for the formation of the bosses consist of endless belts of rubber or molded plastic material such as that indicated at 3. The bosses which produce the constrictions or depressions in the pre-extruded tube are formed by moulding on the said belts, such as illustrated at 4 in Figure 3.

The belts 3 are maintained in guideways 5 and are pressed one against the other in such manner as to form the boss 4, which is an envelope of the product to be obtained. The product is formed as the belts travel forward, the said belts 3 gripping and carrying along the tube extruded around the conductor 6. The belts 3 are driven through gear wheels 8 by means of a driving mechanism not illustrated in the accompanying drawings.

30 The conductor 6 travels between the belts with a continuous linear movement on leaving the extrusion machine, by which the material is injected around the said conductor. The plastic material is injected in the form of a tube by the said extrusion machine, which is partially illustrated at 10 in Figure 2, and the tube thus formed, while still in the plastic condition, then passes between the bosses on the belts 3 and continues its movement so as finally to leave the machine at the same time as the conductor on which it is secured.

35 40 Figure 3 illustrates the formation of the complete boss 4 formed by the pressure of the belts one against the other and their simultaneous travel.

In order to maintain continuous correspondence between the boss portions situated on the belts, that face of the belts which lies opposite the bosses is provided with 45 teeth 7 adapted to engage with gears 8 which control the travel of the said belts.

The moulded teeth 7 may be replaced by a metal chain enclosed in the plastic material of which the belt is formed.

50 The said gears 8 or sprocket wheels are mechanically coupled together in such manner that the boss portions situated on the said belts are always in corresponding positions to one another.

The said belts may be driven by a mechanical driving system adapted in particular to vary the speed of forward 55 movement. Consequently, the speed of production of the extruded article will be determined by the said mechanical system.

On leaving the train of boss forming belts, the product obtained is wound on a bobbin, the movement of which is synchronised with that of the belts in an appropriate manner by means of known devices.

60 The extruded product may also be driven by a hauling winch, in which case the extruded product itself will drive the system of boss forming belts after having been cooled. 65 The choice between these driving means depends upon the dimensions of the extruded product and the available space.

In order to ensure that the extruded product takes the 70 form of the external envelope formed by the bosses provided on the belts, by which envelope the product is given its final form after hardening, air pressure is applied to

the interior of the extruded tube. This air pressure is supplied through an inlet 11 situated, on the side from which the conductor enters, within the extrusion machine, the said conductor passing through the said inlet.

The said pressure, which is of the order of several grammes per square centimetre, ensures constancy of the external form of the extruded and formed insulator.

Should it be desired to obtain an insulation having a small thickness it is advantageous to create around the extruded tube, until it is introduced into the belts, a pressure substantially equal to that introduced into the interior of the said tube.

The injection device necessary for this purpose is illustrated in Figures 4 and 5.

In Figure 4 there is illustrated a nozzle 12 which encloses the extruded tube from the instant when it leaves the extrusion machine until it enters the boss forming belts. The pressure within this nozzle 12 and within the inlet 11 is regulated by a pressure reducing valve 13 and gauged by a manometer 14.

Figure 5 illustrated a modified construction of the arrangement illustrated in Figure 4, this modification being applicable in cases where it is desirable to establish a slight pressure difference between the inlet 11 and the nozzle 12 by reason of the pressure loss occurring in the passage of the air (or other gas) from the inlet 11 to the interior of the extruded tube. In this case, the pressures are individually regulated by the pressure reducing valves 13₁ and 13₂ and gauged by the manometers 14₁ and 14₂.

It is known that the constancy of the external dimensions of the insulator is of great importance in some cases, for example, in the manufacture of an insulated central conductor of a coaxial pair; because it is these dimensions which determine those of the external return conductor, which will subsequently bear against the surface of the insulator, and it is known that disturbances in the transmission of high-frequency currents may occur if the diameter of the return conductor is not constant. The required precision in these dimensions will be obtained under good conditions by the method according to the present invention and will depend solely upon the accuracy with which the bosses are formed on the belts. These will therefore have to be designed and shaped with care in metallic moulds consisting of one or more elements.

The air under pressure may naturally be replaced by any inert gas, such for example as nitrogen.

When the extruded insulation is a thermoplastic material, the hardening must be complete before it leaves the boss forming belts, and both these belts may therefore be steeped in a water-cooling tank or in a tank provided with a cooling system operating by sprinkling or ventilation.

In order to facilitate the cooling and to reduce the length of the boss forming belts, the material of which the said belts consists, for example rubber or silicone, may contain thermally conductive loading agents, such as aluminum powder.

On the other hand, if vulcanisable or thermo-setting materials are employed, the apparatus will be enclosed in a chamber heated to the appropriate temperature and must be of such length as to allow for the time required for the conversion of the material.

If a long train of belts is required, there may be disposed between the gears 8, other gears synchronised therewith, the object of which is to maintain the bosses provided on the belts in corresponding positions and to compensate for the elasticity of the material of which the said belts consist.

In Figure 2, the number of belts employed is two, but this number may be increased, for example to three or four, each belt comprising a corresponding moulding boss element.

It is possible to regulate the gripping action exerted by the belts 3 with the aid of any mechanical locking

device acting on the distance between the axes of the gears 8, and consequently on the pressure exerted by the belts. There is illustrated in Figure 2 one of the control members 9 for this locking device, which may also be adapted to enable the belts 3 to be completely removed for cleaning.

Figures 6, 7, 8 and 9 illustrate by way of example novel and advantageous forms of insulation for a central conductor, which forms can be produced by the method hereinbefore described from a tube of extruded plastic material, simultaneously with the extruding operation. These forms of insulation may be employed with advantage to insulate and support the central conductor of a coaxial pair or conductors of balanced pairs or quads.

Figure 6 illustrates such an insulation manufactured from an extruded polyethylene tube around the central conductor of a coaxial pair. The extruded tube has an external diameter substantially equal to the internal diameter of the tubular return conductor of the said pair.

While the extruded tube is still plastic, depressions 15 are formed with the aid of the apparatus hereinbefore described, the said depressions having the object of maintaining the conductor in position. In this arrangement, the quantity of insulation situated in the neighbourhood of the conductor is very small, which is advantageous from the viewpoint of the transmission of high-frequency currents.

Figure 7 illustrates a modification of this arrangement, in which depressions 16 are transverse instead of longitudinal and are situated face to face in pairs. In another arrangement, the same depressions could be distributed along a helical line.

Figures 8 and 9 illustrate another arrangement in which a tube of polyethylene is extruded around the conductor and thereafter flattened at intervals by small bosses in the form of jaws situated on the boss forming belts 3.

In Figures 8 and 9, the flattening is effected alternately in planes perpendicular to one another. In this arrangement, the quantity of insulating material is reduced in relation to that employed in the arrangement illustrated in Figures 1 and 4, because the diameter *d* of the extruded tube is then smaller than the internal diameter *D* of the return conductor, which will subsequently be applied to the exterior of the insulating tube.

With a given diameter *D*, *d* will preferably be so chosen that:

$$d=0.75D$$

The described insulated conductors may not only be employed as the central conductor of a coaxial pair, but may also advantageously be employed to produce telephone pairs or quads formed by stranding together either two or four insulated conductors as hereinbefore described.

The described apparatus may also be employed for moulding operations and uses other than those hereinbefore described and may be employed for the continuous shaping of any extruded plastic product. Only the boss provided on the belts would be correspondingly modified.

In particular, again with a view to uses for tele-communication purposes, this apparatus may be employed for the insulation of conductors covered with an insulator of a cellular texture of the foam or sponge type.

In such a covering, the insulating product, such for example as polyethylene or polystyrene, is mixed in the extrusion machine with a gas under pressure or with substances which liberate inert gases under the action of temperature.

The hot-extruded product then has the appearance of a foam and has unstable dimensions because it always tends to expand under the action of the internal pressure of the gases by which the multiple cells are filled.

It is consequently difficult to obtain an external contour of exact dimensions, which is frequently a serious

disadvantage, particularly in the case of insulated conductors for telecommunications.

The apparatus described and illustrated in Figures 2 and 3 may be employed with advantage in this case because the external contour of the extruded cellular material will be maintained in close contact with the interior of the boss forming belts 3 during its cooling.

Apparatus similar to those hereinbefore described with reference to Figures 4 and 5 may then be employed with advantage in order to prevent expansion of the cells as they pass from the extrusion machine to the point of admission into the forming belts.

What is claimed is:

1. An apparatus for the continuous shaping of tube formed insulating plastic material around an electric conductor during the hardening of said material, comprising a device for extruding plastic material in a relatively soft state so as to form a tube around said conductor, a plurality of endless belts of elastic material in close contact with each other over a substantial part of their length and each having moulding bosses thereon and further provided with gear teeth for maintaining said bosses in a suitable position in relation to one another and for driving said belts by a sprocket wheel mechanism, said belts forming over said length a closed moulding cavity around said conductor, means for driving said conductor with a continuous movement between said belts at a linear speed equal to that of said belts, means for applying a gas pressure inside said tube, a nozzle through which said conductor is drawn outside said extruding device previously to its being driven between said belts, said nozzle leaving a substantial free space around said conductor and extruded tube, and means for applying in said free space a gas pressure substantially equal to that applied inside said tube.

35

15

20

25

30

2. Apparatus as claimed in claim 1 wherein said belts are of rubber.

3. Apparatus as claimed in claim 1 wherein said belts are of plastic material.

5 4. Apparatus as claimed in claim 1, comprising tubings for introducing into both said extruding device and nozzle a gas pressure controlled by a common regulating valve.

10 5. Apparatus as claimed in claim 1, comprising tubings for introducing into said extruding device and nozzle separately controllable gas pressures controlled by individual regulating valves.

15 6. In a tube forming device wherein a first material is extruded around a second material; a pressure device comprising a first pressure source for introducing a pressure medium between said first and second materials for spacing said materials, a second pressure source for applying a pressure medium to said first material in opposition to the force of the pressure medium applied between said materials, and pressure regulating means to control the pressures applied by said first and second pressure sources to control distortion of the first material.
